UNITED STATES PATENT OFFICE.

OSCAR EVERSON, OF HIBBING, MINNESOTA.

SIGHT-FEED OIL-PUMP.

1,401,145.

Specification of Letters Patent. Patented Dec. 27, 1921.

Application filed July 26, 1920. Serial No. 399,015.

To all whom it may concern:

Be it known that I, OSCAR EVERSON, a citizen of the United States, residing at Hibbing, in the county of St. Louis and 5 State of Minnesota, have invented certain new and useful Improvements in Sight-Feed Oil-Pumps, of which the following is a specification.

This invention relates to lubricators and 10 the primary object of the invention is to provide an improved sight forced feed lubricator for the bearings of steam engines in which a single operating cam is utilized for operating the measuring and forcing 15 pistons for the lubricant.

Another object of the invention is to provide an improved sight feed lubricator embodying a pair of synchronously operated pistons, one of the pistons being adapted to 20 suck in and force the lubricant to the sight compartment and the other piston being adapted to suck the lubricant from the sight compartment and to force the same to the delivery pipe. The pistons being so arranged that on one stroke the lubricant will 25 be sucked from the supply tank and from the sight compartment respectively and on the next stroke forced to the sight compartment and to the delivery pipe respectively. 30 A further object of the invention is to provide a single cylinder block embodying a pair of cylinders rotatably mounted on a suitable supported valve member and a pair of cam operated plungers slidably mounted 35 in the cylinders.

A still further object of the invention is to provide an improved sight force feed lubricator for the bearings of steam engines and the like, of the above character, which is 40 durable and efficient in use, one that is simple and easy to manufacture, and one which can be placed upon the market at a reasonable cost.

With these and other objects in view, the 45 invention consists in the novel construction, arrangement and formation of parts as will be hereinafter more specifically described, claimed and illustrated in the accompanying drawings, forming a part of this specification, in which drawings:

Figure 1 is a transverse section through the improved sight forced feed lubricator.

Fig. 2 is a longitudinal section through the same.

Fig. 3 is a horizontal section through the 55 lubricator.

Fig. 4 is an enlarged fragmentary vertical transverse section through the lubricator illustrating the means for operatively connecting the mechanically operated shaft and 60 the hand operated shaft together.

Referring to the drawings in detail, wherein similar reference character designate corresponding parts throughout the several views, the letter A generally indicates the 65 improved lubricator which includes the supply tank or reservoir B and the operating mechanism C.

The supply tank or reservoir B as shown 70 is of substantially box like configuration and includes the front and rear walls 5 and 6, the side and end walls 7 and 8 and the top and bottom walls 9 and 10. These walls are shown constructed from metal plates but it is to be understood that the reservoir or 75 supply tank may be constructed in any preferred manner and of any desired configuration. The upper wall 9 of the tank or reservoir B is provided with the sight feed compartment 11 which is of substantially frusto pyramidal configuration and is provided with transparent walls 12 which permit of a view being obtained of the interior of the compartment 11.

The operating mechanism C includes a 80 pair of cylinders 13 and 14 and these cylinders are cast in block and have the upper terminals thereof open for the reception of the operating plungers 15 and 16. Suitable

stuffing boxes 17 are provided for the upper 90 ends of the cylinders so as to prevent escape of the lubricant from between the pistons or plungers and the upper ends of the cylinders. The lower ends of the cylinders 13 and 14 are provided respectively with 95 ports 18 and 19. The lower end of the cylinder block is provided with a substantially semi-cylindrical concaved bearing face 20 which rests for swinging movement on the upper surface of the cylindrical solid ported 100 valve block 21. The opposite faces of the cylinder block at its lower end are provided with outwardly extending ears 22 and 23 and these ears have resting against the same, the outwardly extending ears 24 and 105 25 formed on the terminals of the semi-cylindrical strap 26 which engages the lower face of the valve block 21. The ears 22

and 24 are connected by any suitable fastening element 27 while the ears 23 and 25 are connected by a screw 28 which slidably receives the upper ear 23. The screw 28 has coiled around the same a tension spring 29 which engages the upper surface of the ear 23 and normally holds the ears 23 and 25 together. This construction holds the cylinder block and strap 26 in tight engagement with the cylindrical valve block 21. The valve block 21 is provided at its edges, with outstanding annular flanges 30 between which fits the strap 26 and the lower end of the cylinder block. The outer end of the valve block is also provided with a relatively large annular flange 31, which is bolted or otherwise secured as at 32 to the side or end wall 8 of the reservoir or supply tank B. The valve block 21 is provided with a pair of spaced upper ports 32 and 33 and a lower outlet port 34. These ports 32, 33 and 34 are arranged in parallel relation to the axial center of the valve block and extend to the inner surface thereof so as to communicate with the interior of the supply tank or reservoir. The upper ports 32 and 33 are provided with outwardly extending inclined ports 35 and 36 which are adapted to align at predetermined times with the ports 18 and 19 formed in the cylinder block. The lower port 34 is provided with an upwardly inclined port 37 which is adapted to align with the inlet port 18 and this port 34 also has communicating therewith the outlet feed pipe 38. The outlet pipe 38 is connected by suitable coupling 39 to the front wall 5 of the reservoir and extends outwardly of the same. This pipe is then extended to the bearing or bearings to be lubricated. The valve block opposite to the port 34 is provided with a pair of angular related upper and lower ports 40 and 41 and the upper port 40 is adapted to align at certain times with the port 19 and the lower port 41 is adapted to align at certain times with the inlet port 42, which communicates with the reservoir or supply tank. The ports 32 and 33 have communicating therewith the upwardly extending pipes 43 and 44. The pipe 43 communicates with the lower end of the lubricant receiving cup 45 which is carried by the upper wall 9 of the reservoir. This cup as shown projects into the sight compartment 11. The pipe 44 is provided with a goose neck 46 which extends into the sight compartment and the lower end of the goose neck pipe 46 extends directly over the cup 45 and by looking into any one of the transparent walls of the sight compartment the feed of the lubricant can be readily seen.

A pair of shafts 47 and 48 are arranged in axial alignment and extends longitudinally through the tank and are mounted in suitable bearings 49 carried by the side walls of the tank. These bearings are pro-

vided with suitable stuffing boxes so as to prevent the escape of the lubricant through the same. The shaft 47 is provided with a relatively larger diameter than the shaft 48 and is provided with an axial bore 50 for 70 rotatably receiving the inner end of the shaft 48. The shaft 48 has keyed or otherwise secured thereto the eccentric or cam 51 and this cam has mounted thereon a cam strap 52 which is formed in two sections. 75 The lower section 53 is provided with threaded sockets for the reception of the upper reduced threaded ends 54 of the plungers 15 and 16. Thus it can be seen that when the shaft 48 is rotated the plungers 15 and 16 will be alternately raised and lowered and the cylinder block swung on the valve block 21. The outer end of the shaft 48 is provided with a diametrically extending pin 55 and this terminal of the 80 shaft has rotatably mounted thereon a hand crank 56 which is provided with notches 57 for the reception of the pin. It can be seen that when the crank is moved so as to position the walls of the notches in engagement with the pin 55 upon rotation of the crank the shaft will be rotated therewith. The outer end of the shaft 47 is provided with an arm 58 which may be connected to any preferred operating part of the engine with 85 which the sight feed lubricator is associated.

To permit of the turning of the shaft 48 when the shaft 47 is rotated, a ratchet wheel 59 is secured to the inner end of the shaft 48 and this ratchet wheel 59 is adapted to be engaged by a dog 60 which is pivotally connected to the outer end of an arm 61, which is secured in any preferred manner to the shaft 47. To prevent retrograde movement of the ratchet 59 a second pivoted dog 62 is provided for engaging the ratchet wheel 59 and this dog is pivotally carried by a depending bracket 63 which is secured in any preferred manner to the inner surface of the upper wall 9. An expansion 90 spring 64 engages the dog 62 and normally holds the same in engagement with the ratchet wheel. A contractile coil spring 65 is also provided for normally holding the dogs or pawls 60 in engagement with the ratchet 59 and this spring is connected respectively to the arm 61 and the pawl 60.

It can be seen that when the crank 56 is utilized for rotating the shaft 48, no movement will be transmitted to the shaft 47 owing to the ratchet connection.

In operation of the improved lubricator, it can be seen that when the cam moves to the right the pistons 15 and 16 will be gradually raised and the piston block moved to the right or toward the rear end of the casing. This will align the ports 18 and 19 with the ports 35 and 40. This position will be maintained for a few seconds and the oil will be taken in through the port 130

41 which has been moved in alinement with the port 42 through the port 40 then through the port 19 and into the cylinder 16. The oil is also being pumped on this stroke from 5 the pipe 43 through the ports 32, 35 and 18 into the cylinder 13. On the next stroke, when the cam moves to the left or toward the front of the lubricator, the pistons 15 and 16 will be lowered and the cylinder 10 block moved toward the left or the front of the lubricator. This will aline the ports 18 and 19 with the ports 37 and 36, and the oil will be forced from the cylinder 14 to the ports 19 and 36 into the pipe 44 and 15 out of the cylinder 13 to the ports 18, 37 and 34 into the feed pipe 38 where the same is conducted to the bearings. Thus it will be seen that the course of the lubricating oil is as follows: through the ports 42, 41, 40 20 and 19 and into the cylinder 14 and then out of the cylinder 14 through the ports 19, 36 and 33 into the pipe 44 where the same is forced upwardly to the goose neck 46 and 25 into the cup 45 where the feed can be seen by the operator. The oil will then flow down the pipe 43 and will be sucked into the cylinder 13 through the ports 32, 35 and 18 into the cylinder and then out of the cylinder to the port 18, 37, 34 and into the 30 feed pipe.

From the foregoing description it can be seen that an improved and simple form of sight feed lubricator has been provided in which a predetermined amount of lubricating oil will be forced to the bearings on each operation of the lubricator. It can also be seen that the device is so constructed that the plungers or pistons 15 and 16 are operated by a single operating cam.

40 Changes in details may be made without departing from the spirit or scope of this invention; but,

I claim:

1. In a lubricator, a pair of cylinders arranged for synchronous oscillating movement, a pair of plungers arranged in said cylinders for synchronous reciprocating movement, means for operating said plungers and cylinders, a sight feed device, one of said 45 cylinders and plungers forming a means for forcing the lubricating oil to the sight feed device and the other plunger and cylinder forming the means for receiving the oil from the sight feed device and for forcing the oil to the bearing to be lubricated.

2. In a lubricator, a cylinder block including a pair of cylinders having ports formed therein, a ported valve block, means rotatably connecting the cylinder block with 50 the valve block, a pair of plungers slidably mounted in said cylinders, a sight feed device, one of said cylinders and plungers forming a means for forcing the lubricating oil to the sight feed device and the other 55 plunger and cylinder forming means for re-

ceiving the oil from the sight feed device and for forcing the oil to the bearing to be lubricated and a single cam for operating said plungers and cylinder block.

3. In a lubricator, a cylinder block including a pair of cylinders having ports formed in the lower ends thereof, a ported valve block having inlet and outlet ports formed therein and ports for communicating with the ports in the cylinders, a sight feed device, ports formed in said valve block communicating with the pipes of the sight feed device, a pair of plungers slidably mounted in the cylinders and arranged for synchronous movement, and means for operating said plungers, one of the cylinders and plungers forming a means for forcing the lubricating oil to the sight feed device, and the other plunger and cylinder forming means for receiving the oil from the sight 75 feed device and for forcing oil to the bearing to be lubricated.

4. In a lubricator, a cylinder block including a pair of cylinders having ports formed in the lower ends thereof, a valve 90 block, means rotatably mounting the cylinder block on the valve block, inlet and outlet ports formed in the valve block arranged to aline with the ports in the cylinder, a sight feed device, inlet and outlet pipes arranged in the sight feed device, ports communicating with the inlet and outlet pipes, and with the ports formed in the cylinders, one of the plungers and one of the cylinders forming a means for forcing the lubricating oil to the sight feed device, and the other plunger and cylinder forming the means for receiving the oil from the sight 100 feed device and for forcing oil to the bearing to be lubricated, plungers, and a single 105 cam for operating said plungers.

5. In a lubricator, a reservoir, a cylinder block including a pair of cylinders, a port formed in the lower end of each cylinder, a valve block, means rotatably mounting 110 the cylinder block on the valve block, inlet and outlet ports formed in the valve block, the inlet port communicating with the reservoir, an outlet feed pipe communicating with the outlet port, the ports being 115 adapted to aline with the ports formed in the lower end of the cylinders, a sight feed device including a pair of pipes, ports formed in the valve block communicating with said pipes and arranged to aline with 120 the ports in the cylinder block, a pair of sliding plungers mounted in said cylinders, a shaft, a cam mounted on said shaft, and a cam strap arranged to receive said shaft and connected to said pistons, one of said 125 cylinders and one of said plungers forming a means for forcing the lubricating oil to the sight feed device, and one of the plungers and cylinders forming the means for receiving the oil from the sight feed device 130

and for forcing oil to the bearing to be lubricated.

6. In a lubricator, a reservoir, a valve block carried by and arranged in the reservoir, a cylinder block including a pair of cylinders rotatably mounted on said block, a port formed in the lower end of each cylinder, inlet and outlet ports formed in said valve block, the inlet port communicating with said reservoir, an outlet pipe communicating with the outlet port, a sight feed device including a pair of pipes, ports formed in said valve block communicating with said pipes and arranged to align with the ports in said cylinder block, a pair of sliding plungers arranged in said cylinders,

one of said cylinders and one of said plungers forming a means for forcing the lubricating oil to the sight feed device, and one of the plungers and cylinders forming the means for receiving the oil from the sight feed device and for forcing oil to the bearing to be lubricated, a pair of shafts arranged in axial alignment, a cam formed on one of the shafts, a cam strap carried by the plungers and receiving said cam, manual means for operating one of said shafts, mechanical means for operating the other shaft, a ratchet wheel secured to one of the shafts, and a dog mechanism carried by the other shaft.

OSCAR EVERSON.
